UNITED STATES PATENT OFFICE.

PAUL J. HUEBER, OF SYRACUSE, NEW YORK.

CONCRETE BUILDING FORM.

Application filed June 6, 1923. Serial No. 643,742.

To all whom it may concern:

Be it known that I, PAUL J. HUEBER, a citizen of the United States of America, of Syracuse, in the county of Onondaga, in the State of New York, have invented new and useful Improvements in Concrete Building Forms, of which the following, taken in connection with the accompanying drawings, is a full, clear, and exact description.

10 This invention relates to concrete building forms of the class set forth in my Patent #1,421,236, June 27, 1922, in that the main object is to provide a temporary form composed of standardized easily portable sections capable of being progressively and rapidly assembled from the bottom upward one or more stories to enable the walls, floors and partitions to be progressively cast or molded from concrete into a unitary or

15 20 monolithic structure and to be expeditiously stripped and reassembled in other parts of the same building or in different buildings as the concrete work is finished.

One of the specific objects is to provide simple and efficient means supported by the studs at one side of a wall for receiving and supporting the panels at the opposite side of the same wall and thereby to avoid the necessity of duplicating the studding at both 30 sides of the wall, resulting in a considerable saving of time, labor and material.

Another object is to provide a more convenient and expeditious mechanism for locking the studs and floor joists to the girders and also for locking the meeting ends of 35 sectional girders to each other, whereby the wall faces of the studs and girders and the floor faces of the joists and girders including those of the girder sections, may be properly alined to produce the desired smooth finish of the adjacent surfaces of the wall and floor and at the same time to enable those parts to be easily and quickly detached one from the other when it is desired to 40 strip them from the walls.

Other objects and uses relating to specific parts of the forms will be brought out in the following description.

In the drawings, Figure 1 is a perspective view of the inner portion of one corner of

one story of a building form, omitting parts of the wall panels, but showing parts of the floor panels and the essential features of the invention assembled ready for use, the central portions of the form being broken away 55 and the outer wall forms omitted except in part.

Figure 2 is an enlarged detail sectional view taken on line 2—2, Figure 1, showing the means for attaching the floor joist to the 60 girder.

Figure 3 is a sectional view taken on line 3—3, Figure 2.

Figure 4 is an enlarged detail sectional view taken on line 4—4, Figure 1, showing 65 the means for attaching the upper end of one of the studs to the superposed girder together with one of the tie bolts for supporting portions of the outer wall form.

Figure 5 is a sectional view taken on line 70 5—5, Figure 4.

Figure 6 is an enlarged detail sectional view taken on line 6—6, Figure 1, showing the means for connecting the lower end 75 of the stud to the lower girder together with one of the tie bolts for supporting portions of the outer wall form.

Figure 7 is an enlarged detail horizontal sectional view taken on line 7—7, Figure 1, showing the means for connecting the adjacent 80 ends of the girder sections.

Figure 8 is a sectional view taken on line 8—8, Figure 7, except that the girder sections are shown full width.

Figure 9 is an enlarged detail horizontal 85 sectional view in the plane of one of the tie bolts showing portions of the opposite wall forms and one of the spacing members partly broken away together with the means for clamping the outer panels against the adjacent end of the spacing members.

Figure 10 is a perspective view of a portion of one of the bearing plates for the edges of the adjacent outer panels.

In order that the various adaptations of 95 this invention may be clearly understood, I have shown portions of the form as used in the construction of one of the upright corner walls and floor of a building although it will be evident that certain parts of the same 100

form may be used in the construction of the concrete partitions, as a unitary or monolithic part of the walls and floors as will be hereinafter more fully explained.

5 As illustrated, the form comprises lower and upper girders —1— and —1'— suitably supported in parallel horizontal planes one above the other, a distance corresponding approximately to the required distance 10 between the floors of the building, said girders being constructed of comparatively light channel steel bars of substantially the same cross sectional size and form.

The lower girder —1— may be supported 15 edgewise vertically upon a previously constructed concrete footing-course —a— which may be a part of the foundation of the building or one of the concrete floors thereof, which is to become a part of the monolithic structure, said girder being arranged with its flat side facing the space in which the concrete wall is to be constructed so as to constitute a part of the form for said wall.

20 25 It is necessary to make these girders in sections for convenience in handling and to couple the sections together end to end in exact alinement with each other, and in order that this may be done expeditiously, 30 the channelled sides of the adjacent ends of the sections are provided with coupling members —3— and —4— riveted or otherwise permanently secured to their respective sections, as shown more clearly in Figures 35 7 and 8.

The section —3— preferably consists of an angle iron having its base flange riveted to the web of the girder —1— and its other flange offset laterally some distance beyond 40 the longitudinal edges of the flanges of the girder, and provided with a stop shoulder —5— and a transverse slot —6— just at the outside of the shoulder —5— for receiving a tapered key or wedge —7—.

45 50 55 60 65 The other coupling member —4— is also provided with a base flange riveted or otherwise secured to the web of the girder and has a lateral offset terminating in a longitudinally extending hook-shaped extremity —8— having a slot —9— opening from the underside for receiving the lateral offset portion of the coupling member —3—, the distance between the web of the girder and hook-shaped extension —8— being approximately equal to the distance between said web and the inner end of the slot —6— so that when the hook-shaped extremity —8— is placed over and upon the offset portion of the coupling member —3—, the wedge key —7— may be driven into said slot to simultaneously wedge against the outer end of the extension —8— by which operation, the adjacent ends of the girder sections will be alined with each other, both vertically and transversely, and will be rigidly

held in such position until the key —7— is removed, whereupon they may be readily separated one from the other by relative lateral or vertical displacement.

A series of hollow cast metal brackets 70 —10— are riveted or otherwise secured to the web of the girder —1— in longitudinally spaced relation, a predetermined distance apart from center to center according to the length of the panel most convenient for handling which is determined by actual experience so that the size of the panels and consequently the spacing of the brackets —10—, and construction of various other parts of the form may be standardized for all ordinary classes of work.

75 80 85 90 95 A plurality of upright studs —11— corresponding in number to the number of brackets —10— are supported at their lower ends upon the upper faces of the girders —1— and brackets —10— as shown more clearly in Figure 6, and it therefore, follows that these studs will be arranged in spaced relation, lengthwise of the girders, a distance between the centers of the brackets to assist in supporting the panels as —12—, in upright positions as will be hereinafter more fully described.

The brackets —10— extend outwardly 95 some distance beyond the flanges of the girder and constitute coupling members for cooperation with companion coupling member —13— on the lower ends of the studs —11—.

100 105 110 115 120 The distance between the inner and outer faces of the stud —11— is substantially equal to the distance between the inner face of the girder and outer face of the bracket —10— so that when the stud rests upon the girder with its inner face substantially co-incident with that of the girder, its outer face would be substantially co-incident with the outer face of the bracket.

This bracket is provided with a boss 110 —14— projecting outwardly beyond its outer face and provided with a transverse slot —15— for receiving a tapered key or wedge —16—.

115 120 125 130 The coupling member —13— preferably consists of a cast metal plate secured by rivets or equivalent fastening means to the outer face of the stud —11— and extended downwardly beyond the lower end of said stud so as to overlap upon the corresponding outer face of the bracket —10— and is provided with a vertical slot —17— opening from its lower end for receiving the boss —14— and permitting the key —16— to wedge tightly between the outer face of the coupling member —13— and outer wall 125 of the slot —15— thereby securely fastening the lower end of the stud to the girder and also permitting said stud to be readily removed from said girder by simply withdrawing the key.

The lower face of the bracket —10— is disposed in substantially the same horizontal plane as that of the girder —1— so as to rest upon the concrete footing-course 5 —a— while the upper face rises to the height of the level of the corresponding face of the girder, but is beveled outwardly and downwardly to form a seat for the lower end of the stud and to permit said 10 stud to be more easily stripped or withdrawn when released by the removal of the key —16—.

The upper girder —1'— is supported upon the upper end of the studs —11— with 15 its inner flat face substantially co-incident with the corresponding face of the posts or studs and therefore, in the same vertical plane as that of the lower girder —1— and is provided with a plurality of hollow brackets 20 —10'— similar to the lower brackets —10— in that they are riveted or otherwise secured to the web of the upper girder in vertical alinement with the lower brackets and adapted to rest upon the upper ends of the studs 25 which are provided with coupling members —13— similar to the lower coupling members —13—.

That is, each upper bracket —10'— constitutes a coupling member for cooperation 30 with the coupling member —13'— in securing the girder to the upper end of the stud —11— and for this purpose is provided with a boss —14'— having a transverse slot —15'— for receiving a tapered key —16'— 35 similar to the key —16— while the companion coupling member —13'— is bolted or otherwise secured to the outer face of the said stud —11— to extend upwardly from the upper end thereof and is provided with 40 a lengthwise slot —17'— open at the top for receiving the boss —14'—.

When the lower or upper girders —1— or —1'— meet at an angle or corner of the building, the meeting ends are provided 45 with a pair of brackets —10— or —10'— and coupling members —13— and —13'— those of each pair being in juxtaposed relation or integral with each other in which case one boss as —14'— or —14— and one 50 tapered key as —16— or —16'— is sufficient for each pair, by driving the keys —16— and —16'— diagonally through corresponding slots —15— and —15'— and across the outer edges of the overlapping portions of 55 the coupling members —13— and —13'— as shown in Figure 1.

A sheet metal plate —18—, Figure 9, is secured by bolts —19—, or equivalent fastening means, to the inner face or wall side of 60 each stud —11— to project beyond the opposite upright sides thereof, and thereby, to form stop flanges —18'— for the adjacent edges of the panels —12— which are placed from the outside between the studs and 65 against said stops so as to substantially fill

the intervening spaces between the lower and upper girders and between the upright studs where they are held in place by turn buttons —20— on the outer faces of the studs as shown in Figure 1. 70

That is, the parts —20— are mounted on pivotal bolts —21— projecting from the outer faces of the studs —11— and extend radially in opposite directions a sufficient distance so that when turned to one position, 75 their opposite ends will overlap upon the outer faces of the adjacent ends of the panels to hold the latter against outward displacement and when turned to another position parallel with the stud, will lie wholly between the opposite sides of the stud to permit the panel to be withdrawn outwardly or away from the wall. 80

The lower and upper faces of the brackets projecting beyond the flanges of the girder —1'— are substantially flat and disposed in planes substantially co-incident with the corresponding faces of the girder so as to rest squarely upon the upper ends of the studs —11— and against the underside of the 90 floor panels as —22—, Figure 1.

An angle bar —23— has one of its flanges secured by rivets or other suitable fastening means to the lower face of the upper girder —1— and its other flange projecting downwardly therefrom in a plane substantially co-incident with the inner face of the girder so as to form a continuation thereof, and also to constitute a stop flange —24— for the upper ends of the studs or posts and panels —12— as shown more clearly in Figures 2 and 4, the inner faces of the upper edges of said panels being recessed at —25— to receive said flanges —24— while the upper end of the plate —18— is cut away at —26—, 100 Figure 1, to receive the same stop flange —24— whereby the inner faces of both girders together with that of the panels and of the stud —11— and the inner face of the stop flange —24— will lie in substantially 110 the same flat plane to form a corresponding flat face on the concrete wall as the latter is progressively built up against those parts.

The panels —12— may be made in sections of suitable height most convenient for handling and are placed edgewise one upon the other from the bottom upward as the work progresses until the spaces between the studs and girders are filled, said panels being preferably made of laminated wood and reinforced at the ends by cleats —12'— of such thickness that when added to that of the main body of the panel, makes the entire thickness of the panel through the cleats substantially equal to the corresponding thickness at the studs so that their inner and outer faces may be substantially coincident with the corresponding faces of the adjacent stud, while the buttons —20— engaging the outer faces of the cleats when turned at 120 125 130

right angles to the stud serve to hold the adjacent ends of the panels in engagement with the flanges —18'— and —24—.

The parts thus far described are used to form one side of an upright wall or partition and of course, are to be continued around all sides of the inclosure or such parts thereof as may require concrete walls.

10 *Outer wall forms.*

When these girders and posts are properly assembled or coupled together in the manner described, they are utilized to support the companion forms for the opposite faces of the wall, and for this purpose, the lower and upper brackets —10— and —10'— and their corresponding girders —1— and —1'— are provided with transversely registering bolt openings —27— for receiving suitable tie bolts —28—, the intermediate portions of the studs being provided with similar bolt openings —27'— for receiving similar tie bolts —28'—, all of said bolts being free to slide in their respective openings and are provided at one end with heads —30— adapted to engage the outer faces of the brackets —10— and —10'— and studs —11— for limiting their movement in one direction.

30 All of the tie bolts —28— and —28'— are of substantially the same size and therefore, interchangeable, and are of sufficient length to extend through and some distance beyond the wall space for receiving and supporting concrete spacing sleeves —b— and a metallic stop plate —31— against which, the companion panels —32— are adapted to rest when placed in operated position.

40 The spacing sleeve preferably consists of concrete blocks precast to the desired length corresponding to the thickness of the wall which is to be constructed and are formed with central lengthwise openings —b'— therethrough for receiving the tie bolts —28— and —28'— said concrete sleeves being incorporated in the concrete wall to remain a permanent part thereof, while permitting the withdrawal of the tie bolts in stripping the form from said completed walls.

50 When the tie bolts —28— and —28'— are placed in operative position, the sleeves —b— are slipped over the smaller ends thereof so as to abut at one end against the stop plates —31— after which the stop plates —31— which are apertured to receive said bolts are placed over the smaller ends thereof and against the adjacent ends of the sleeve —b— and are then locked in place by means of tapered keys —34— passing through transverse slots —35— in the bolts adjacent the outer faces of the stop plates —31— so that opposite edges of the key —34— will be wedged against the plate —31— and opposite wall of the slot —35—

to firmly clamp said plate to the adjacent end of the sleeve and at the same time, clamp the opposite end of the sleeve tightly against the stop plate —31— thereby rigidly clamping the bolts to the brackets —10— and —10'— and to the studs —11— independently of the panels —32— and —12—.

These plates —31— are adapted to be used as a part of the form for the outer surfaces of the outer walls of a building and may be made of any suitable lengths convenient for handling and assembling, end to end, one upon the other during the progressive building, as the studs and girders for the various floors are erected, said plates being preferably of less width than the opposite stop plates —31— and are provided intermediate their upright edges with outwardly projecting vertical flanges —36— at one side of the bolt openings so as to form dividing partitions between the adjacent edges of the panels —32— and also to form stop flanges against which the inner faces of the upright edges of the panels may abut to limit the inward movement of said panels.

These panels —32— are somewhat similar to the panels —12— in that they are made of laminated wood and provided with reinforcing cleats —32'— near their opposite upright edges, the only difference being that they are somewhat longer to correspond approximately to the distance between the flanges —36— of the plates —31—.

The outer end of each tie bolt —28— and —28'— extends between the adjacent ends of the panels —32— and some distance beyond the outer faces of the cleats —32'— and are provided with transverse openings —37— for receiving tapering keys —38— which engage metal wearing plates 39 on the outer faces of the cleats —32— and also engage the outer end wall of the slot —37— for clamping the adjacent ends of the panels between the wedge and opposite edges of the stop plate —31— and also permitting the removal of the panels independently of said stop plates by simply removing the key —38—.

115 *Floor forms.*

The floor panels —22— upon which the concrete floors are made are supported upon the upper faces of the girders —1'— and brackets —10'— and are additionally supported by one or more floor joists —40— which are preferably made of light sheet metal of the I-beam type supported edge-wise vertically by the girders through the medium of suitable coupling members presently described with their upper faces in substantially the same horizontal plane as that of the girder —1'— for receiving and supporting the meeting ends of the panel sections, the latter being provided on their under sides with stop cleats —22'— adapted

to engage one side of the joist for properly aligning the panels therewith and holding them against endwise displacement so that the ends of the panels may meet along the 5 longitudinal center of the upper face of the joist, it being understood that the joists are assembled on the girders in spaced relation, a predetermined distance apart and that the panels are made of corresponding lengths 10 and therefore, standardized.

The means for coupling the ends of the joist to the girders is shown more clearly in Figures 2 and 3, and comprises a pair of brackets —41— secured at one end by rivets —42— to the web of the girder —1— within the channel thereof, and in longitudinally spaced relation slightly greater than the thickness of the web of the joist, the other ends of said brackets being provided 15 with a pair of horizontal slots —43— and a vertical slot —44— registering with similar slots in the web of the adjacent end of the joist —40— for receiving tapered keys —45— and —46— whereby the joist is 20 detachably supported by the brackets and may be released therefrom by simply removing the wedges.

That is, the portions of the brackets having the slots —43— and —44— extend some 30 distance beyond the flanges of the girder —1— so that the joist may be placed between them from the underside upwardly and locked in place by the insertion of the keys —45— and —46— in their respective 35 openings in the brackets and joist, thereby temporarily holding the joist in operative position and permitting the same to be removed by downward displacement by simply removing the keys after the concrete 40 floor has been formed.

Operation.

The footing-course or foundation —a— having been previously formed and leveled, 45 the girders —1— with the brackets —10— will then be placed in operative position thereon and each made in sections, the sections being coupled together by the coupling members —3— and —4—, and tapered 50 keys —7—.

The studs or posts —11— are then individually erected and coupled at their lower ends to the girder —1— by means of the coupling members —10— and —13—, and tapered keys —16—, and the buttons —20— adjusted lengthwise of their respective 55 posts.

The upper girder sections with the brackets —10— thereon are then placed in operative 60 position upon the upper ends of the post and clamped thereto by means of the tapered keys —16—.

The floor joists —40— are then lifted into 65 place and coupled to the girders by means of tapered keys —45— and —46— thus pro-

ducing a self-supporting skeleton structure for receiving the inner wall panels —12— and floor panels —22— which, as previously stated, are made in easily portable sections for convenience in handling and are 70 placed in operative position by hand, the wall panels —12— being held in place by turning the buttons —20— crosswise of the studs so as to overlap upon the cleats of the adjacent panels. 75

In placing the outer forms for the walls in operative position, the tie bolts —28— and —28'— are first inserted through their respective openings in the brackets —10— and —10'—, girders —1— and —1'—, and 80 posts —11—, until their heads rest against the inner faces of the posts and brackets, after which the concrete sleeves —b— are placed over and upon the outer ends of the 85 portions of the tie rods which extend across the wall space.

The stop plates —31— are then placed over and upon the protruding ends of the tie bolts and together with the sleeves are clamped in place by the keys —35— ready 90 to receive the outer panels —32— which are placed in operative position by hand and are clamped in place by the keys —38— thus producing a vertical space between the panels for the reception of the concrete wall 95 which may be filled in from the top and may be continued across and upon the floor panels —22— so as to homogeneously unite the concrete of the floor and walls into a monolithic structure. 100

The lower edge of the lowermost panel —32— rests upon the footing course —a— while the several panels may be arranged edge to edge one upon the other, and carried to a height above the level of the floor 105 line when necessary.

After the concrete wall and floor are completed and properly set so as to be self-sustaining, the forms may be stripped and reused for the next succeeding story for economy in the use of a limited number of forms although it is evident that as soon as the concrete floor is finished as a unitary part of the wall, other form sections similar to those described may be used in the construction of the second story and superposed floor and so on through the several stories. 115

In stripping the forms from the completed walls and floors, it is simply necessary to remove the keys —38— whereupon the panels —32— may be removed one by one from the top downward and laid aside, after which the keys —35— may be removed thus permitting the removal of the plates —31—, sleeves —4— and bolts —28—. 120

The buttons —20— may then be turned lengthwise of the studs —11— to permit the removal of the wall panels —12— after which the keys —16— and —16'— and 130

—45— and —46—, and if necessary the key —7— may be removed to permit the removal of the parts held thereby in such order as may be most convenient, which, of course, would allow the floor panels —22— to drop away from the concrete floor for convenience of removal, all of which affords a more expeditious stripping of the forms, than has heretofore been practiced.

10. The particular structure of the various parts of the form shown and described also enables those parts to be standardized and used extensively for various kinds of work on the same or different buildings, and also 15 reduces to a minimum the amount of materials necessary to carry in stock for such forms.

A further and more important advantage of this structure is that it avoids the use of 20 nails, screws or similar fastening means in that all parts are secured together by tapered keys or buttons which are easily removed or adjusted to permit the removal of those parts.

25. I claim:

1. In a temporary form for concrete buildings, the combination of lower and upper girders, upright posts supported in spaced relation upon the lower girders and 30 supporting the upper girder and provided with laterally projecting stop flanges, separate devices for coupling and uncoupling the ends of each post to and from the adjacent girders, panels inserted in the spaces 35 between the posts and girders and against said stop flanges, and stops on the posts movable into and out of engagement with the panels for holding and releasing the latter against and from the stop flanges.

40. 2. A temporary form for concrete buildings including a girder having a substantially flat inner face next to the wall to be formed and provided with a bracket projecting from its opposite face, a post having its lower end resting upon the bracket, and cooperative means on the bracket and post for holding said post against lateral movement on the bracket.

50. 3. A temporary form for concrete buildings including a girder having a substantially flat inner face against the wall, a post having its lower end resting upon the upper edge of the girder with its inner face next to the wall substantially co-incident with 55 that of the flat face of the girder, coupling members secured respectively to the girder and to the post to overlap one upon the other when the posts are placed in operative position for alining the inner face of the post with that of the girder, and movable means for clamping and releasing the overlapping parts one upon the other.

60. 4. A temporary form for concrete walls including a girder having a substantially flat inner face adjacent the wall, a post hav-

ing its lower end resting upon the girder and provided with a substantially flat inner face co-incident with that of the girder, coupling members secured respectively to the girder and to the post to overlap one upon the other, when the parts are assembled, one of said members being provided with a projection extending through a slot in the other member, and a key movable in an opening in the projection across said slot.

5. A temporary form for concrete walls including a girder having a substantially flat inner face adjacent the wall, a post having its lower end resting upon the upper edge of the girder with its inner face substantially co-incident with that of said girder, a coupling secured to the girder directly under the post to partially support the same, and provided with an outwardly extending projection having a transverse opening, a separate coupling member secured to the lower end of the post and extending across the outer face of the first named member to overlap upon the outer face of the first named member when the parts are assembled, and provided with a slot for receiving said projection, and a key movable in said opening across the outer face of the second named member and across 95 said slot.

6. A temporary form for concrete walls including a girder, having a substantially flat inner face next to the wall, a post having its lower end resting upon the upper edge of the girder with its inner face substantially flat and co-incident with that of the girder, a coupling member secured to the girder directly below the lower end of the boss for partially supporting the same and 100 having its outer upright face substantially co-incident with that of the post, said member being provided with a projection extending outwardly from its outer face and provided with a transverse opening, a separate coupling member secured to the lower end of the post to overlap upon the outer face of the first named member, and provided with arms at opposite sides of said projection, and a key movable in the opening in said projection and engaged with the outer faces of said arms.

7. A temporary form for concrete walls including a girder having a substantially flat inner face adjacent the wall, a coupling member secured to and projecting outwardly from the outer face of the girder, a post having its lower end resting upon the upper face of the bracket, the adjacent faces of said member and post being beveled 115 outwardly and downwardly to facilitate withdrawal of the post from the girder, and means including a tapered key for locking the post to the bracket, the inner face of the post being substantially coincident with 125

that of the girder when the parts are adjusted for use.

8. A temporary form for concrete building including a post, support means therefor, a girder supported upon the upper end of the post with its inner face substantially co-incident with that of the post, a coupling member secured to and projecting outwardly from the outer face of the girder directly over the post, a separate coupling member secured to the upper end of the post and overlapping upon the outer face of the first named member, and means including a key for locking the overlapping portions 10 of said members, one upon the other.

9. A temporary form for concrete buildings, including an upright post having a substantially flat inner face adjacent the wall, supporting means for said post, a girder supported upon the upper end of the post and provided with a substantially flat inner face, co-incident with that of the post, a coupling member secured to and projecting outwardly from the outer face of the girder directly over the upper end of the post and provided with an outwardly extending projection having a transverse opening, a separate coupling member secured to the upper end of the post to overlap upon the outer face of the first named member and provided with arms engaging opposite sides of the projection and a tapered key movable in said opening and against said arms for locking the overlapping portions of the coupling members 30 against each other.

10. A temporary form for concrete buildings including lower and upper girders having substantially flat inner faces adjacent the wall, an upright post having its lower end resting upon the upper edge of the lower girder, and supporting at its upper end, the upper girder coupling members secured to and projecting from the outer faces of said 40 girders directly below and directly above the corresponding ends of the post and provided with outwardly extending projections, having transverse openings therethrough, additional coupling members secured respectively to the lower and upper ends of the post, and overlapping upon the outer faces of the adjacent first named members, and each provided with a slot for receiving the corresponding projection, and 50 tapered keys movable in the openings in said projections for clamping the second named members to the first named members.

11. A temporary form for concrete buildings, including a sectional girder having its sections arranged end to end and its adjacent end provided with coupling members, said members having flanges crossing each other, one of said flanges having a slot for receiving the other flange, said other flange 60 having a transverse opening, and a tapered

key, inserted in the opening, and against the first named flange, across the slot.

12. A temporary form for concrete buildings including a girder, a floor joist extending laterally from the girder at an angle 70 thereto, a bracket secured to the girder and overlapping upon the adjacent end of the floor joist, the overlapping portions of the bracket and floor joist being provided with registering openings therethrough, and tapered keys movable in said openings for clamping the joist to the bracket and permitting it to release therefrom when the key 75 is removed.

13. In a temporary form, for concrete 80 walls, an upright post and supporting means therefor, at one side of the wall, tie rods extending loosely through transverse openings in the post across and some distance beyond the wall space, concrete spacing 85 sleeves loosely mounted on the rods and abutting at one end against the inner face of the post, an upright apertured plate at the opposite side of the wall slidably mounted on the tie rods to and from a position 90 against the adjacent ends of the sleeves, tapered keys movable in transverse openings in the tie rod and across the outer face of the plate to hold said plate and sleeve in operative position, panels abutting against 95 said plate at opposite sides of the tie rod, and additional tapered keys movable in transverse apertures in the tie rod and against the outer faces of the panels to hold the latter against said plate. 100

14. In a temporary form for concrete buildings, a horizontal footing-course, a girder supported edgewise upon the footing-course, and having a substantially flat inner face adjacent one side of the wall, upright posts 105 supported at their lower ends upon the upper edges of the girders and provided with substantially flat inner faces co-incident with that of the girder, couplings connecting the lower ends of the posts to the girder, stop 110 flanges projecting from opposite sides from the inner faces of the posts, means for supporting the upper ends of the post against lateral movement, panels movable into and out of the spaces between the posts and adapted to rest against said stop flanges when adjusted for use, stop members on the outer faces of the posts movable into and out of engagement with said panels for holding the latter against the stop flanges when 115 adjusted to one position and for releasing the panels when adjusted to another position, upright stop plates directly opposite the posts and in spaced relation thereto, tie rods extending loosely through registering 120 openings in each set of opposed posts and plates, spacing sleeves loosely mounted upon the tie rods between each post and its corresponding plate, devices movable on the tie rods for clamping the plate against the adja- 125 130

cent end of the steel and for simultaneously forcing the sleeve endwise against the inner faces of the posts, panels abutting against the outer faces of the plates, and devices 5 movable on the tie rods for clamping said panels against plates when moved to one position and for releasing said panels when moved to one position and for releasing said panels when moved to another position.

10 15. In a temporary form for concrete buildings including lower and upper girders forming parts of the form for one side of an upright wall, upright posts supported at their lower ends upon the lower girders and 15 supporting at their upper ends, the upper girders, separate couplings connecting the lower ends of the posts to the lower girders, additional couplings connecting the upper ends of the posts to the upper girders, panels 20 movable in the spaces between the girders

and posts, additional upright wall forms in transversely spaced relation to the girders, posts and panels, a floor joist extending laterally from the upper girder, a coupling connecting said floor joist to the upper 25 girder, and floor panels supported upon the upper faces of the upper girders and floor joists wholly at one side of the wall face of the upper girder, whereby the wall space between the upright forms may open into space 30 above the floor panels to permit the concrete floor and wall to be molded as a monolithic unit.

In witness whereof I have hereunto set my hand this 22nd day of May, 1923.

PAUL J. HUEBER.

Witnesses:

H. E. CHASE,
RITA CAMPOLIETO.
